Dexter, Mich.

Application September 30, 1942, Serial No. 460,262

1 Claim. (Cl. 20—78.3)

This invention relates generally to mats and constitutes a continuation in part of our application filed March 30, 1942, bearing Serial No. 436,902.

One of the essential objects of the invention is to provide a safety mat that has preferably been developed from materials other than those considered vital and necessary at this time for defense purposes.

Another object is to provide a non-slip mat that is preferably constructed entirely of wood or equivalent non-metallic material having sufficient softness to eliminate or substantially reduce fatigue of persons using it as a tread structure.

Another object is to provide a solvent resisting mat capable of being cleaned with chlorine solutions for sanitation purposes.

Another object is to provide a sectional mat capable of being folded or rolled into a compact package for any purpose such as shipment, storage, or when it is desired to clean the floor upon which the mat is placed.

Another object is to provide a strong and durable mat that is simple in construction, inexpensive to manufacture, efficient in use and easy to repair.

Another object is to provide a sectional mat that is so constructed that it may conform to irregular or wavy floor surfaces.

Another object is to provide a mat of the type described wherein the tread sections thereof have suitable dimensions to provide adequate foot support, are low enough to minimize the hazard of accidental falls, and are high enough to discourage standing with one foot off and one on the mat.

Another object is to provide a fibrous mat that is so constructed that it has a certain degree of resiliency to cushion the feet of persons thereon but is solid enough to withstand relatively heavy loads.

Another object is to provide a grating type of mat wherein all tread sections except those at opposite longitudinal side edges thereof are freely mounted upon the pivot elements therefor. Thus, the sections of the mat may be assembled with a minimum of fastening elements.

Other objects, advantages and novel details of construction of this invention will be made more apparent as this description proceeds, especially when considered in connection with the accompanying drawing, wherein:

Figure 1 is a fragmentary top plan view of a mat embodying our invention;

Figure 2 is a side elevational view thereof;
Figure 3 is an end view thereof;
Figure 4 is a fragmentary top plan view of a slight modification;
5 Figure 5 is a vertical sectional view through a portion of the structure illustrated in Figure 4;
Figure 6 is a fragmentary side elevational view of another modification;
Figure 7 is a fragmentary end view of another modification.

Referring now to the drawing, A are the tread sections, B are the pivot elements therefor, and C are the spacers of a mat embodying our invention.

15 As shown, the tread sections are in the form of oblong blocks and are preferably formed of fibrous material such as soft textured wood. However it is obvious that the tread sections may be formed of any suitable material. Any number of the blocks A may be used depending upon the size and shape of the mat desired, however in the present instance the mat is substantially rectangular in shape and the blocks A extend longitudinally thereof in substantially parallel rows. Preferably the blocks A in each row are spaced longitudinally apart so that (1) the blocks in adjacent rows overlap each other at opposite ends thereof, and (2) the blocks in alternate rows are spaced laterally apart in transversely extending rows. To facilitate proper drainage of liquids such as oils, water and the like under the mat between adjacent rows thereof, the blocks A are provided in their lower edges substantially midway their ends with transversely extending 30 downwardly opening open ended channels 10 which may be any width desired to cooperate with the floor or other supporting surface for the mat to provide transversely extending passages for the liquids.

40 The pivot elements B for the blocks A are in the form of straight rods and extend transversely of the mat from one side to the other thereof. Such rods have a uniform cylindrical cross section throughout their length and engage longitudinally spaced transversely extending holes 11 in the blocks. Preferably these pivot elements B are also made of wood. However, it is obvious that they may be made of any suitable material. As shown, each block is engaged by two of the pivot elements B. Hence, all blocks A are uniformly engaged by the pivot elements B, and special end formations for such elements are unnecessary and have been dispensed with entirely.

45 The spacers C are sleeved on the pivot elements B at opposite end of the mat and are lo-

55

cated between alternate rows of the blocks A. Such spacers C may be any configuration such as square, round, etc., but are substantially equal in width to the width of the individual blocks.

If desired, the outermost and central longitudinal rows 12, 13 and 14, respectively, of blocks may have a greater depth than the other rows intermediate the same, as illustrated in Figures 2 and 3. Thus, the intermediate rows are in effect suspended above the floor by the pivot elements B passing through the blocks thereof. As stated above the entire mat, including the pivot elements B thereof, is made of wood, hence the suspended rows of blocks provide the user of the mat with a yielding structure that cushions the strain of standing thereon, and thereby reduces fatigue.

Inasmuch as the intermediate rows of blocks just mentioned are elevated relative to the floor there are two relatively wide longitudinally extending channels 15 and 16, respectively, provided beneath said blocks for drainage purposes. Hence, the transversely extending drainage channels 10 in the blocks A of the outermost and central rows 12, 13 and 14, respectively, only will normally be effective. However, notwithstanding this, all of the blocks A in the mat are provided with such channels 10 as it is much easier and less expensive to mill all alike and thus avoid separate forming operations and special sorting and assembling operations.

In Figures 4 and 5 we have illustrated a slight modification wherein (1) all rows of blocks have the same depth, and (2) the blocks A' in the outermost rows 20 and 21 are rigidly secured to the pivot elements B'. Preferably the pivot elements B' are made of hickory wood and are secured to the outermost blocks by means of vertical pegs or pins 22 that also are preferably made of wood. Obviously these pegs or pins may be formed of any suitable material. As shown, these pegs 22 extend completely through the blocks A' from top to bottom thereof and pass substantially diametrically through the pivot elements B' so as to provide efficient connections between the parts and thereby eliminate as far as possible any shear of the pegs at their juncture with the pivot elements B'. Thus, in this construction, all other blocks A' intermediate the outer rows 20 and 21, respectively, may be loosely sleeved on the pivot elements B' and will be held against displacement by the pegged outer rows of blocks. Moreover, round spacers 23 which require no securing means are preferably used in this construction. Consequently the over-all number of fastening elements has been reduced to a minimum.

In Figures 6 and 7 we have illustrated two other modifications wherein substantially wedge-shaped extensions of certain of the blocks are provided for safety purposes to improve the approaches to the mat. In Figure 6 the blocks A² at either end of the mat may be provided with substantially wedge-shaped endwise extensions 30 providing sloping approaches 31 to the top surface of the mat from the floor or other supporting surface for the mat, while in Figure 7 the blocks A³ at either side of the mat may have substantially wedge-shaped lateral extensions 40 providing sloping approaches 41 to the top surface of the mat.

In use, the all wood grating type of mat structure embodying our invention may be laid as illustrated in Figures 1 and 4, respectively, upon any floor, such as a concrete, cement or other hard floor of a factory or other commercial building, or may be mounted on top of box cars or other rolling stock, as a walkway for trainmen, or may be laid upon decks or platforms of ships, or directly upon the ground in military or construction camps, etc., as desired. In fact, it is adapted for use as a tread structure in any suitable location. When not in use, the mat may be folded or rolled as desired into a relatively compact unit. Thus, the mat may be easily and conveniently shipped from one place to another, or stored or moved out of the way when it is desired to clean the floor or other supporting surface beneath the mat. Due to its construction, the mat may conform to an irregular floor or other supporting surface and will always permit the proper drainage of oils, water or other liquids on the floor beneath the mat.

The soft textured wood blocks and hickory wood pivot elements and pegs provide an all wood combination that possesses numerous advantages. For example, the all wood construction of the mat (1) tends to reduce fatigue of the user thereof, (2) permits the mat to absorb and be impregnated with oils, greases, etc., which tend to enhance the wearing qualities thereof, (3) is solvent resisting, (4) can be cleaned by chlorine solutions for sanitation purposes, (5) is rustproof and (6) will not deteriorate when washed by ordinary cleaning solutions. It should also be appreciated that the mat embodying our invention can be made wholly or partially or salvaged woods or equivalent materials. Moreover, it is apparent that glue, cement or a suitable adhesive may be used instead of the pegs 22 to secure the blocks in the outermost rows of the structure to their pivot elements such as B' or B. Thus, it will be apparent that an all-wood mat embodying our invention is a definite improvement upon all-metal, all-rubber, or composite structures.

What we claim as our invention is:

A yielding mat structure having tread sections and pivot elements therefor, the tread sections being in the form of oblong blocks and arranged in longitudinally spaced relation in substantially parallel longitudinally extending rows, the blocks in adjacent rows overlapping each other at opposite ends thereof, the blocks in alternate rows being spaced laterally apart in transversely extending rows, the pivot elements extending transversely of the structure from one side to the other thereof and engaging longitudinally spaced transversely extending holes in the blocks, the outermost and central longitudinally extending rows of blocks having a greater depth than the other longitudinally extending rows intermediate the same, whereby said outermost and central rows constitute floor or ground engaging elements, and the other intermediate rows are suspended above such floor or ground from the pivot elements therefor.
